UNITED STATES PATENT OFFICE.

STANLEY KWIECINSKI, OF MILWAUKEE, WISCONSIN.

SAFETY LOCK.

Application filed August 31, 1921. Serial No. 497,406.

I have illustrated my invention as embodied in a chest lock, but the form illustrated is merely one of convenience inasmuch as the invention is applicable to any other form of lock which is provided with a sliding bolt.

The purpose of my invention is the production of a lock which cannot be operated by an ordinary form of key, but which requires a key of special construction, coupled with a knowledge of the peculiar organization of the lock in order to operate the same. The invention therefore affords a safe guard against being tampered with, and enables the owner of the chest to which the lock is applied, to have the assurance that the contents of the chest will not be disturbed in his absence.

The lock embodying my invention is economical in construction, and may be applied without difficulty to the chest or other article which it is intended to secure.

Referring now to the drawing which is attached hereto,

Figure 1 is a vertical sectional view on the line 1—1, Fig. 3, looking from the front of a chest of ordinary construction, and showing the lock in position.

Fig. 2 is a diagrammatic view of the arrangement of the locking mechanism and showing the manner of its operation.

Fig. 3 is a vertical sectional view on the line 3—3, Fig. 1, looking in the direction of the arrow, and showing the lock in position on the inside of the front wall of the chest.

In the drawings, the numeral 10 indicates the front wall of a chest, and 11 the cover thereof. The keeper 12 is attached to the under side of the cover 11 in the usual manner, the said keeper having one or more projections 14 depending therefrom. These projections are perforated or notched as at 15, in the usual manner for engagement therewith of the bolt 16 of the lock.

A back plate 17 supports the sliding bolt 16 and its associated mechanism, such bolt being guided in its position by supporting pins or rollers 18 which are carried by the said back plate. The manner of the engagement of the sliding bolt with the keeper of the lock is well known, whereby when the cover of the chest is lowered, it will be retained until reverse movement of the bolt occurs under the influence of the proper key. A spring 19, which may be of any

suitable form is secured at one end to the back plate 17, such spring bearing with its free end against the bolt 16 and normally urging it into its closed and operative position. The parts thus far described may be of usual and well known form.

Ordinarily the spring pressed sliding bolt is directly engaged by the key of the lock to reverse the position thereof and open the lock. Locks of that type do not afford any security against being tampered with and are easily operated by many keys, and can be picked with various devices or instruments.

In constructing my safety lock I pivot a depending thrust member 20 to the bolt 16, engagement of the free end or point of the member 20 with the key being necessary to operate the bolt and open the lock. A stop 21 set in the back plate 17 determines the normal position of the depending member 20 and a spring 22, of suitable form and secured at one end to the back plate 17, urges the said depending member 20 into its position of normality.

A key 23 of peculiar construction may be supported by the post 24 of the lock as usual. The said key is provided along the edge of the bit with a notch 25, extending parallel with the shank thereof. When the key is inserted in the lock and rotated in the direction of the full line arrow, Fig. 2, the edge of the bit of key will wipe past the free end of the depending member 20, swinging the latter upon its pivot, against the stress of the spring 22. When the bit passes the free end of the said depending member, the spring 22 immediately snaps the said member into its normal position in contact with the stop pin 21. Reverse movement of the key will bring the right side of the bit of the key against the left side of the depending member 20, without operating the bolt of the lock. The operation just described will occur in the event that

some one unauthorized to do so, attempts to open the lock. But in the hands of the owner, the key will be slowly turned in the direction of the full line arrow in Fig. 2, until the pointed end of the depending member 20 snaps into the notch 25 in the edge of the bit of the key. The parts will then be in the position shown in Fig. 2, and a reverse movement of the key, or a movement in the direction indicated by the dotted line arrow in the said Fig. 2, will cause

the member 20 to act with an angular thrust upon the latch 16 of the lock, and force the same to the rear against the stress of the spring 19, and thus release the keeper 5 of the lock from its engagement with the bolt, all as indicated by the dotted line positions of the parts in Fig. 2. The cover 11 of the chest may thereupon be raised.

A front plate 26 may be attached to the 10 back plate 17, in the usual manner to enclose the mechanism of the lock. As an additional means for preventing tampering with the lock, I may attach to the front plate 26 a blade spring 27, such blade being 15 provided with a notched projection 28, which latter extends through a curved slot 29, formed in the front plate 26, as shown 20 in Fig. 1. The notch in the projection 28 will receive the free end of the depending member 20, and prevent the vibration thereof until after the force of the spring 27 has been overcome and the notched projection 28 is withdrawn from its engagement with the member 20.

To enable the notched member 28 to be 25 disengaged, I bevel the edge thereof at the right of the member 20, as shown at 29' in Fig. 3. When the proper key is applied to the lock and rotated, the bit of the key will 30 engage the bevelled edge 29' of the projection 28, and force the spring 27 outwardly into a recess 30, formed in the front wall of the chest for the clearance thereof. In 35 the further movement of the key, the depending member 20 will be swung on its pivot, until engagement of the key and point of the said member is effected in the manner hereinbefore described. The projection 28 being withdrawn from its engagement with the member 20, the further movement 40 of the key will push the member 20 to one side, in which position it will prevent the spring 27 from returning when the key passes the notch therein. The force of the 45 spring 22, being superior to that of the spring 27, will return the member 20 to its normal position when the key is withdrawn from its engagement with the said projection.

Having thus described my invention, 50 what I claim and desire to secure by Letters Patent by the United States, is:

1. In a safety lock, a casing, a bolt slid-

ing therein, a depending thrust member pivoted on the bolt, a fixed stop in the casing 65 adapted to limit the movement of the pivoted thrust member in one direction, a spring bearing upon the thrust member and acting normally to hold it in engagement with the fixed stop, a key for engaging the 70 thrust member and moving it away from the stop to bring the point of the thrust member and the edge of the bit of the key into operative engagement, whereby upon reverse movement of the key the thrust 75 member will slide the bolt.

2. In a safety lock, a bolt sliding therein, a depending thrust member pivoted on the bolt, a fixed stop in the casing adapted to limit the movement of the pivoted thrust member in one direction, a spring bearing 80 upon the thrust member and acting normally to hold it in engagement with the said stop, a key having a notched bit for engaging the thrust member and moving it 85 away from the stop against the pressure of the spring to bring the free end of the thrust member and the notched bit of the key into operative engagement, whereby upon reverse movement of the key the thrust member will slide the bolt into unlocking position.

3. In a safety lock, a bolt sliding therein, a depending thrust member pivoted on the bolt, a fixed stop in the casing adapted to 90 limit the movement of the pivoted thrust member in one direction, a spring bearing upon the thrust member and acting normally to hold it in engagement with the said stop, a key having a notched bit for 95 engaging the thrust member and moving it away from the stop against the pressure of the spring to bring the free end of the thrust member and the notched bit of the key into operative engagement, whereby upon reverse movement of the key the thrust member will slide the bolt into unlocking position, and a spring having a notched member 100 for engaging the thrust member to retain the latter until the spring is withdrawn by the key.

In testimony whereof, I have signed my name at Milwaukee this 20th day of August, 1921.

S. KWIECINSKI.
